UNITED STATES PATENT OFFICE.

EMERSON B. BIRD, OF SEATTLE, WASHINGTON.

APPARATUS FOR RAISING AUTOMOBILES.

1,291,734.

Specification of Letters Patent.

Patented Jan. 21, 1919.

Application filed June 25, 1918. Serial No. 241,869.

To all whom it may concern:

Be it known that I, EMERSON B. BIRD, a subject of the King of Great Britain, residing at Seattle, in the county of King and 5 State of Washington, have invented certain new and useful Improvements in Apparatus for Raising Automobiles; and I do hereby declare the following to be a full, clear, and exact description of the invention, such as 10 will enable others skilled in the art to which it appertains to make and use the same.

This invention relates to lifting mechanism, and more particularly to an elevator for raising automobiles, vehicles or other 15 organizations to facilitate the operation of a mechanic upon the underneath parts of the vehicle.

It is one of the objects of the present invention to provide a simple, practicable, 20 and comparatively inexpensive elevating mechanism onto which a vehicle can be readily run and then elevated to a suitable height to permit a mechanic or workman to have ready access to the lower portion beneath the body of the vehicle.

Another object of the invention is to provide means to facilitate the running of the vehicle onto the elevator and to provide 30 means for guiding the vehicle to prevent its side running, and a particular object of the invention is to provide an elevator which may be erected at any convenient location without the requirement of alteration to the surrounding structure and without 35 requirement of excavating or providing a pit or the like.

With the above and other objects in view as will be rendered manifest to those skilled in the art, the invention consists of the construction in combination, and in details of arrangements of the parts as more particularly hereinafter described relative to an embodiment of the invention, illustrated in the accompanying drawing, in which—

45 Figure 1 is a side elevation of the elevator;

Fig. 2 is a bottom plan view of the same, and

Fig. 3 is an end view.

50 As illustrated, the elevator comprises a substantially rectangular frame having strong longitudinally extending side members 2 of suitable proportions and dimensions which are bent upwardly at their ends 2' and formed with a horizontal portion 2^a to be secured as by rivets or other suit-

able means 3 to the transverse end members 4 formed to lie in the same plane with the main body of the side members 2, and which have their ends bent upwardly at 4' and horizontally at 4^a where they are overlapped by the horizontal ends 2^a and riveted thereto at 3. This rigidly constructed frame may be placed at any convenient location, and between and parallel to the side members extend wheel rails 5 having their longitudinal edges turned upwardly as at 5^a for a suitable distance, and are also provided with upturned lateral and outwardly inclined arms 5^b upon which are suitably secured threaded nut or bearing portions 6 to take each a complementary screw 7, the lower ends of which rest upon ball bearings 8 mounted on the horizontal supports 2^a and the lower ends of which screws 7 are turned 75 down to pass through the frame structure, and each at its lower end carries a beveled gear 9 which meshes with a set of beveled gears 10 and 11, these being respectively secured on transverse end shafts 12 and 80 horizontally extending side shafts 13, all of said shafts being mounted in suitable bearings 14 secured to the respective frame members and projecting beneath the overhanging supporting portions 2^a and 4^a, 85 which being elevated above the bottom plane of the frame form a convenient recess for the gear sets, the frame section, also protecting these gears against injury by virtue of this location.

90 Obviously, the arrangement of the gearing connecting the several shafts may be altered or of any suitable type or construction, and as here shown one of the shafts is extended as at 13^a to carry and be driven by a pulley wheel or other suitable means indicated at 15.

95 To facilitate the running of a vehicle on to the wheel track 5 the ends of these may be provided with extensions 5^c which may be turned down to an inclined position outwardly to permit the ready running of the wheels upwardly to the plane of the tracks 5 which are disposed just above the transverse shafts 12. When not in use the track 100 sections 5^c can be folded upwardly and over the adjacent ends of the tracks 5.

105 To provide for the necessary stability of the lifting screws 7, which obviously will be of such direction of pitch that when the 110 driven shaft 13 is operated the nuts or threaded blocks 6 will be simultaneously

and uniformly lifted by the rotation of the screws, these screws will be supported by braces 18 attached at their lower ends to the frame corners and provided at their 5 upper ends with bearings 19 engaging reduced portions 7^a at the heads of the screws.

What is claimed is:

1. An elevator for vehicles, comprising a frame having side and end sills with up-
10 turned and overhanging ends, a set of up-
right screws having fixed bearings in said
ends, means for uniformly actuating the
screws including shafts overlying said sills
and journaled in the upturned part, a
15 pair of spaced independent track members,
and individual brackets on the screws con-
necting said members to the adjacent screws
whereby the former may be uniformly ele-
vated, said frame adapted to be located flat
20 upon a surface over which a vehicle may be
run onto the track-way, the tracks having
ends deflected toward the plane of the sur-
face, the shafts having gears all arranged
above the bottom of the frame.
- 5 2. An elevator for vehicles, comprising a
stationary frame, a set of upright screws
having fixed bearings, shafts and gears for
uniformly actuating the screws, a pair of
spaced independent track members, and
30 brackets connecting each of said members to

respective screws at the sides of the frame
whereby the members may be uniformly ele-
vated, said frame having sills adapted to be
located flat upon a surface over which a
vehicle may be run onto the track-way, the 35
corners of the frame up-set to form hous-
ing for the gear-mechanism of the driving
means and through which upset part the
shafts extend.

3. A stationary elevator for wheeled ve- 40
hicles, comprising a pair of side sill mem-
bers turned vertically and thence horizon-
tally endwise, cross or end members of simi-
lar form all rigidly connected at overlapped
ends, bearings on the upright parts of the 45
sill members and shafts supported therein
and extending along and over the members,
threaded shafts journaled in the corners of
the frame formed by the said members,
braces mounted on the frame and having 50
bearings engaging the upper ends of the
threaded shafts, a carrier arm on each
threaded shaft, relatively disconnected
tracks each extending beside the adjacent
55 side member and connected to the pair of
carriers at its side of the frame and gears
connecting the several shafts to simultane-
ously raise or lower the tracks.

In testimony whereof I affix my signature.
EMERSON B. BIRD.
